[57] CLAIM

The ornamental design for a hand held spotlight, as shown and described.

DESCRIPTION

FIG. 1 is a top, front perspective view of hand held spotlight showing our new design, the electric cord being shown in broken lines for illustrative purposes only;

FIG. 2 is a right side elevational view thereof on an enlarged scale, the left side being a mirror image;

FIG. 3 is a front elevational view thereof on an enlarged scale;

FIG. 4 is a top plan view thereof on an enlarged scale;

FIG. 5 is a rear elevational view thereof on an enlarged scale;

FIG. 6 is a bottom plan view thereof on an enlarged scale.

FIG. 1

FIG. 4

FIG. 2
